INVENTOR:

ANNA S. TURNQUIST.

BY Whiteley and Ruckman

ATTORNEYS.

UNITED STATES PATENT OFFICE.

ANNA S. TURNQUIST, OF MINNEAPOLIS, MINNESOTA.

TOILET CASE.

Application filed December 13, 1923. Serial No. 680,482.

To all whom it may concern:

Be it known that I, ANNA S. TURNQUIST, a citizen of the United States, residing at Minneapolis, in the county of Hennepin and State of Minnesota, have invented certain new and useful Improvements in Toilet Cases, of which the following is a specification.

My invention relates to toilet cases, and 10 an object is to provide a receptacle in which face powder and a powder puff may be conveniently carried without liability of the powder being spilled. Another object is to provide a device of this character which 15 can be carried in a hand bag or purse so that a supply of powder may always be available for use whenever desired. An object in particular is to provide a device of this character in which the powder may be readily 20 supplied to the puff in the desired quantity without the necessity of shaking the powder out of the receptacle or inverting the receptacle.

The full objects and advantages of my invention will appear in connection with the 25 detailed description, and the novel features of my inventive idea will be particularly pointed out in the claims.

In the accompanying drawings which illustrate two forms in which the invention may be embodied,—Fig. 1 is an elevational view of the device. Fig. 2 is a view in central vertical section. Fig. 3 is a view in horizontal section on the line 3—3 of Fig. 2. 35 Fig. 4 is a view similar to Fig. 2 but showing a movable member of the device in depressed position. Fig. 5 is a view in horizontal section on the line 5—5 of Fig. 2. Fig. 6 is an elevational view showing the 40 powder receptacle removed from the outside case. Fig. 7 is a fragmentary sectional view on an enlarged scale. Fig. 8 is a view in central vertical section showing a modified construction.

Referring first to the construction shown in Figures 1 to 7, I provide an outside case 10, having a hinged cover 12 secured to the underside of which is a mirror 14. The outside case is adapted to contain a powder receptacle which has a vertical wall 16 engaged by a leaf spring 18 secured to the bottom of the outside case near the periphery thereof whereby the powder receptacle may be firmly held in place in the case. The vertical wall 16 at its upper end is turned inwardly to form an annular flange 20, the

inner margin of which is bent to form a downwardly inclined portion 22. A perforated diaphragm 24 is so positioned as to form an upper wall of the powder receptacle, and this diaphragm is normally held in engagement with the flange 20 and the inclined portion 22 by a coiled spring 26 placed in the powder receptacle and engaging the bottom thereof. In order to guide the diaphragm 24 for reciprocating movement, two rods 28 are secured within the vertical wall 16 at diametrically opposite places, and these rods are received in openings at the margin of the diaphragm. The provision 70 of the inclined portion 22 of the flange 20 produces a central depression for receiving a powder puff. The margin of the diaphragm 24 is preferably downwardly inclined as shown in Fig. 7 to constitute a vertical flange 30 in order that powder may not escape at the margin of the diaphragm. In order to prevent discharge of powder from the receptacle upon the puff when such operation is not desired, 75 a perforated disk 32 may be centrally attached to the diaphragm 24 by a rivet 33 so that the perforations of the disk and diaphragm may be brought into and out of register upon turning the disk 32, the 80 amount of rotation of the latter being limited by an attached lug 34 extending through a slot 36 in the diaphragm. A handle 38 is hingedly attached to the diaphragm so that the powder receptacle may be lifted out of 85 the case for refilling the receptacle through an opening in its bottom provided with a closure 40 pivotally attached at 42 and having a catch 44.

In the form of the invention shown in 90 Fig. 8, the case and powder receptacle are combined into a single unit. The case 10 is provided with an internal annular flange 46 and with a coiled spring 48 which normally holds a perforated diaphragm 50 in 95 engagement with said flange. Rods 51 secured within the case serve as guides for the diaphragm during its reciprocating movements. A perforated disk 52 rotatably attached to the diaphragm 50 by a 100 central rivet 54 provides for shutting off the discharge of powder when desired. The space below the diaphragm 50 which constitutes a compartment for powder is filled through an opening in the bottom of the 105 case provided with a closure 56.

The operation and advantages of my in-

vention will now be readily understood. Sufficient space is provided between the diaphragm and cover of the case for containing a powder puff. When the diaphragm is 5 depressed in opposition to the upward thrust exerted by the coiled spring, powder will be forced through the perforations and will be received by the underside of the puff. It is evident that the amount of powder supplied to the puff will be determined by the force with which the diaphragm is depressed; and further, that the amount supplied may be increased by depressing the diaphragm several times. The amount supplied 10 may be decreased by slightly turning the perforated disk so as to bring its perforations partly out of register with those in the diaphragm. Whenever it is desired to entirely shut off the supply of powder to the 15 puff or to prevent escape of powder from the powder compartment, the perforated disk is turned to bring its perforations out of register with the perforations in the diaphragm.

I claim:

25 1. A toilet case comprising a boxlike member, a perforated diaphragm slidably mounted in said member and forming the upper wall of a compartment for powder in the lower portion of said member, fixed rods 30 in said compartment for guiding said diaphragm during its reciprocating movements, spring means for resiliently holding

said diaphragm upwardly, and a cover for said boxlike member.

2. A toilet case comprising a boxlike member, 35 an annular flange in said member, a perforated diaphragm slidably mounted in said member and forming the upper wall of a compartment for powder in the lower portion of said member, a coiled spring in 40 said compartment for resiliently holding said diaphragm upwardly in engagement with the lower surface of said annular flange, fixed rods in said compartment for guiding said diaphragm during its reciprocating movements, and a cover for said 45 boxlike member.

3. A toilet case comprising a boxlike member, a powder receptacle removably contained in said member; an annular flange 50 at the upper end of said receptacle, a perforated diaphragm slidably mounted in said receptacle and constituting the upper wall thereof, a coiled spring in said receptacle for resiliently holding said diaphragm 55 upwardly in engagement with the lower surface of said annular flange, rods secured within said receptacle for guiding said diaphragm during its reciprocating movements, and a cover for said boxlike member. 60

In testimony whereof I hereunto affix my signature.

ANNA S. TURNQUIST.
